UNITED STATES PATENT OFFICE.

WILLIAM LIPPERT, OF KENOSHA, WISCONSIN, ASSIGNOR TO HENRY RICHARDSON, OF CHICAGO, ILLINOIS.

WIRE FABRIC.

1,329,782.

Specification of Letters Patent.

Patented Feb. 3, 1920.

Application filed July 10, 1914. Serial No. 850,103.

To all whom it may concern:

Be it known that I, WILLIAM LIPPERT, a citizen of the United States, residing at Kenosha, in the county of Kenosha and State 5 of Wisconsin, have invented certain new and useful Improvements in Wire Fabrics, of which the following is a specification.

This invention relates to improvements in wire link fabrics of that type extensively 10 used to form bed and couch bottoms, and pertains more particularly to that type of fabric which is made in comparatively light wire, the requisite strength being secured through the avoidance of open or unsecured 15 ends of the wire anywhere in the line of longitudinal strain. The general object of the invention is to provide an improved, simple and strong link fabric of the light wire type, and one which will readily lend 20 itself to manufacture by comparatively simple and easily performed machine operations.

In wire fabrics which include a series of longitudinally disposed strands of links, said 25 strands being flexibly connected together by means of a series of laterally disposed rows of cross-connecting members having free or unsecured hooked ends, the wire used in the making of the said cross-connecting 30 members, whether cross links or cross arms, cannot be any lighter than is essential to positively prevent their free or unsecured hooked ends from straightening out under the strain imposed upon them when 35 the fabric is in use. A distinctive feature of my present invention resides in the employment of a two-ply or twin wire cross arm, the two members of which cross arm are independent of each other and are offset 40 from the plane of the body member and, when connected to a transversely adjacent link, divide the lateral strain between them and afford much greater strength than a cross arm formed by a single ply of wire.

45 For the purpose of end-to-end connection of the links, one end of each link has the two limbs of the body or tension member connected preferably by a simple U-bend of the wire, while the other end may have 50 simply an offset from the horizontal plane of the body or tension member of the link, the remaining portion or portions of the wire extending laterally from said offset to form the cross arm, and the offset being engaged by the U-bend or equivalent connec-

tion of an adjacent link; or, in lieu of a mere offset, the wire may be bent to form a complete terminal loop and the remaining portion or portions of the wire be extended laterally from said loop to form the cross arm. 60 If desired, a portion of the wire may be extended laterally on the side of the link opposite the cross arm to form a lateral loop or eye for engagement with the free end of the cross arm of a laterally adjacent link. 65

Another feature of the invention that, in its broad aspect, is independent of the particular form of cross connecting member employed—whether cross arm or cross link, and whether single or two-ply, and is also 70 independent of the specific form of body member or end loop—applies to that embodiment of the invention herein shown, wherein, in lieu of a simple downwardly offset portion of the wire for engaging the 75 U-bend or equivalent portion of an endwise adjacent link, the body member is provided at that end with a hook or loop member that may be formed as an extension of either or both limbs of the body member; and in such 80 case the cross-connecting member is formed with a terminal portion that embraces both sides of said hook or loop member, so that the terminal hook or loop of the cross-connecting member serves to hold the unsecured 85 end of the hook or loop extension of the body member against pulling or straightening out under tensional strain.

In the accompanying drawings I have 90 illustrated my invention in a variety of specifically different forms, all of which, however, embody the basic principle of the invention; and referring thereto—

Figures 1, 4, 7, 10, 13, 16, 19 and 22 are fragmentary top plan views of several 95 slightly varying forms of my fabric;

Figs. 2 and 3 are sectional details on the corresponding lines of Fig. 1;

Figs. 5 and 6 are sectional details on the corresponding lines of Fig. 4;

Fig. 8 is a sectional detail on the line 8—8 of Fig. 7;

Fig. 9 is a perspective detail, showing an alternative offset arrangement at the connected ends of two longitudinally adjacent 105 links;

Fig. 11 is a sectional detail on the line 11—11 of Fig. 10;

Fig. 12 is a perspective detail of the structure of Fig. 10;

Fig. 14 is a sectional detail on the line 14—14 of Fig. 13;

Fig. 15 is a perspective detail of the structure of Fig. 13;

5 Fig. 17 is a sectional detail on the line 17—17 of Fig. 16;

Fig. 18 is a perspective detail of the structure of Fig. 16;

10 Fig. 20 is a sectional detail on the line 20—20 of Fig. 19;

Fig. 21 is a perspective detail of the structure of Fig. 19; and

Fig. 23 is a sectional detail on the line 23—23 of Fig. 22.

15 In all of the several embodiments of the invention illustrated, the bent wire link is so formed as to provide a two-ply body or tension member 5, the limbs of which are preferably united at one end by a simple

20 U-bend 6. In the form shown in Figs. 1 to 3 inclusive the wires at the end opposite the U-bend 6 of the body member 5 are downwardly offset relatively to the plane of the body member 5, as shown at 7, and the end

25 portions of the wire are thence extended laterally in substantially parallel relation to form a two-ply cross arm 8, the free end of which terminates in a two-ply hook 9; and the free end of this hook is formed with a

30 reentrant bend or reversely facing hook 10 which prevents the terminal hook 9 from slipping out of place when the fabric is in use or is flexed or folded upon itself. Fabrics with cross arms when used on

35 couches and other like articles having folding sides may have the hooked ends of their cross arms forced open and displaced, and the employment of the reentrant form of hook above described, by preventing this, has

40 a particular advantage. When the fabric is assembled the U-bend 6 of one link engages the offset portions 7 at the base of the cross-arm 8, as clearly shown in Fig. 3, and the twin terminal hooks 9 of the cross-arm are carried around the body member 5 of a laterally adjacent link.

The form shown in Figs. 4, 5 and 6 modifies the form of Figs. 1 to 3 inclusive, in that one of the limbs of the body member 5, 50 instead of connecting with the cross arm by a simple downwardly offset portion, is formed with an inwardly extending loop member 11, the inner end of which is thence extended laterally to form one member of

55 the two-ply cross arm 12, and the terminal hook 13 of the cross arm lies between the two members of the laterally adjacent cross arm and embraces both the upper and lower sides of the terminal loop of the body mem-

60 ber. This form of the invention embodies and illustrates the feature referred to in the preamble of this specification of restraining the unsecured side or end of a terminal loop or hook member, formed on the end of the 65 link opposite the end having the U-bend 6

or equivalent connector, against opening out, by causing the terminal portion of the cross connecting member to embrace it.

In the form shown in Figs. 7 and 8, the body member 5 has the twin offset 14 at one 70 end, but from one of said offsets the wire forming the same is first extended on the side opposite the cross arm to form a lateral loop or eye 15, and is thence extended across the body member 5 to form one limb of the 75 two-ply cross arm 16; and the terminal hook 17 of the cross arm is engaged with the lateral eye 15 of a laterally adjacent link. The U-bend of the longitudinally adjacent link embraces the twin offset portions 14 of the 80 wire, the same as in Figs. 1 to 3. Fig. 9 illustrates an alternative form in which the lateral offset is formed at the opposite end of the body member; that is, one limb of the cross arm 16 and the lateral eye 15 extend 85 substantially in the horizontal plane of the body member 5, and the U-bend of the endwise adjacent link is given a downward offset to engage said parts, as shown at 18. This modification can be embodied in the 90 form of the invention shown in Figs. 10 to 12 next described, it being immaterial at which end of the link the offset is formed.

The structure of Figs. 10, 11 and 12 differs from that of Figs. 7 and 8 merely in 95 that the wire forming the lateral eye 19 is bent outwardly of the end of the body member, instead of inwardly thereof, so that the relative position of the two limbs of the cross arm 20 is reversed, and one of said 100 limbs lies beyond the double offset 21 instead of inwardly thereof.

The several forms shown on sheet 2, and comprising Figs. 13 to 23 inclusive, all present, in lieu of an offset or shoulder in the 105 wire at the junction of the body member and cross arm, a complete terminal loop for engagement with the U-bend of an endwise adjacent link. In the form of Figs. 13, 14 and 15, the two limbs of this terminal loop 22 extend substantially parallel and are both carried up and across the body member side-by-side, merging into the two-ply cross arm 23, the two limbs of which preferably diverge outwardly or toward their outer end and are 115 formed with reentrant terminal hooks 24 which embrace the body member of a laterally adjacent link and straddle the inner end of the cross arm of said laterally adjacent link. The construction shown in Figs. 16, 17 and 120 18 is a modification of that of Figs. 13, 14 and 15 wherein the two limbs of the cross arm 25 are spaced at their inner ends and converge toward their outer ends. As a consequence of this, the two limbs of the terminal loop 26 are of different lengths, as most 125 clearly shown in Fig. 18, and the two-ply hook 27 at the free end of the cross arm 25 is confined between the spaced limbs of the cross arm of a laterally adjacent link. 130

The structure of Figs. 19, 20 and 21 embodies a modification of the structures of Figs. 13 to 18 inclusive, to provide a lateral loop or eye for engagement by the free end 5 of the cross arm. In this case one member 28 of the two-ply terminal loop is carried up on one side of the body member and thence across the latter to merge into one limb of the cross arm 29, and the other 10 member 30 of said loop is carried up on the other side of the body member thence across the latter in the opposite direction to form the lateral loop or eye 31, and thence back across the body member, merging 15 into the other limb of the cross arm. The hooks 32 on the free ends of the cross arms engage with the lateral loops or eyes 31 of laterally adjacent links.

In the form of Figs. 22 and 23, the two-ply terminal loop takes the form of a complete curl 33, the wire being extended thence lengthwise of the body member 5 and beyond the end of the latter and being thence bent laterally to form the two-ply cross arm 34. The U-bend 6 of an endwise adjacent link is carried through the curl 33, and one limb of the body member thereof overlies both limbs of the cross arm 34. The terminal hook of the cross arm 30 preferably embraces one limb of the body member and also one of the longitudinal extensions of the curl 33, as clearly shown in Fig. 22.

It will be observed as a feature common 35 to all of the forms shown and described that the invention entirely eliminates the presence anywhere in the longitudinal strands, which are subjected to the greatest strain, of all free or unsecured ends of the 40 wires forming the individual links. The construction, therefore, affords a high degree of tensile strength both in the longitudinal strands and in the cross-connections, enabling the latter to be made in 45 much lighter wire than the present standard fabrics. The several forms are, furthermore, of comparatively simple construction, and do not require any highly organized or complicated machine for their 50 manufacture.

Where the fabric herein presented is employed for bed and couch bottoms, which is its principal intended use, it will be understood that in the case of the longitudinal 55 row of links forming one marginal strand the cross arms are, of course, unnecessary and are dispensed with; the stub ends of the wire beyond the terminal offsets or loops of the body member being suitably 60 cured to the latter in any convenient manner to secure the strength and permanency of the longitudinal connections of the links.

I claim:

1. A wire link fabric including a plurality of links or units, each composed of

a single piece of wire bent to form a two-ply body member the two limbs of which are cross-connected at one end, a two-ply cross arm, and an integral joining portion at the other end of said body member uniting 70 said cross arm and body member; said links being assembled end-to-end with the cross connection of one link connected with the joining portion of an endwise adjacent link and with the free end of the cross arm 75 flexibly engaged with a link of an adjacent strand.

2. A wire link fabric including a plurality of links or units, each composed of a single piece of wire bent to form a two-ply 80 body member having at one end a two-ply cross-arm offset at its junction with the body member relatively to the plane of the latter and at the other end a connecting portion uniting the two limbs of said body 85 member and also engaging the offset at the base of the cross-arm of an endwise adjacent link to form longitudinal strands, said longitudinal strands being laterally connected together by means of the cross arms. 90

3. A wire link fabric including a plurality of links or units, each composed of a single piece of wire bent to form a two-ply body member with a U-bend at one end and a two-ply cross-arm at the other end 95 offset at its junction with the body member relatively to the plane of the latter, said links being assembled end-to-end with the U-bend of one link engaged with the offset at the base of the cross arm of an end- 100 wise adjacent link, and with the free ends of the cross arms flexibly engaged with the links of an adjacent strand.

4. A wire link fabric including a plurality of links or units, each composed of 105 a single piece of wire bent to form a two-ply body member comprising the intermediate portion of the wire and a two-ply cross-arm comprising the end portions of the wire, said body member at one end having a U-bend of the wire connecting the two limbs thereto, and said cross-arm at its inner end being offset at its junction with the body member relatively to the plane of the latter, said links being assembled end-to- 110 end with the U-bend of one link engaged with the offset at the base of the cross-arm of an endwise adjacent link and with the free ends of the cross-arms flexibly engaged with the links of an adjacent strand. 115

5. A wire link fabric, including a plurality of assembled links or units, each formed with a two-ply body member and a two-ply terminal loop, both limbs of said loop being extended crosswise of the body 120 member from the same side of the latter, and forming a two-ply cross-arm to engage an adjacent link. 125

6. As a new article of manufacture, a wire fabric link formed with a two-ply body 130

- member and a two-ply terminal loop, both limbs of said loop being extended crosswise of the body member from the same side of the latter, and forming a two-ply cross-arm 5 to engage an adjacent link.
7. A wire fabric including a plurality of links or units, each composed of a single piece of wire bent to form a two-ply body member consisting of an intermediate portion of the wire and a two-ply cross arm consisting of the two end portions of the wire, one limb of said cross-arm leading off from one limb of the body member and the other limb of said cross-arm leading off from the other limb of the body member; said links being connected end-to-end to form longitudinal strands and having the outer ends of their cross-arms connected to the links of an adjacent strand. 10
- 15 8. A wire fabric including a plurality of links or units, each composed of a single piece of wire bent to form a two-ply body member and a two-ply cross-arm, said cross-arm consisting of the free end portions of the wire and having its two limbs independent of each other and united to said body member by portions of the wire that are inflected relatively to the plane of said body member; said links being connected end-to-end to form longitudinal strands and having the free ends of their cross-arms connected to the links of an adjacent strand. 20
- 25 9. As a new article of manufacture, a wire fabric link or unit consisting of a single piece of wire bent to form a two-ply body member consisting of an intermediate portion of the wire and a two-ply cross-arm consisting of the two end portions of the wire, one limb of said cross arm leading off from one limb of the body member and the other limb of said cross-arm leading off from the other limb of the body member. 30
- 35 10. As a new article of manufacture, a wire fabric link or unit consisting of a single piece of wire bent to form a two-ply body member and a two-ply cross-arm, said cross-arm consisting of the free end portions of the wire and having its two limbs independent of each other and united to the said body member by portions of the wire that are inflected relatively to the plane of said body member. 40
- 45 11. A wire fabric including a plurality of links or units, each composed of a single piece of wire bent to form a two-ply body member consisting of an intermediate portion of the wire and a two-ply cross arm consisting of the end portions of the wire, the two limbs of the said body member being 50 united at one end of said body member and

unconnected at the opposite end of said body member; said links being connected end-to-end to form longitudinal strands and having the outer ends of their cross arms connected to the links of an adjacent strand. 65

12. As a new article of manufacture, a wire fabric link consisting of a single piece of wire bent to form a two-ply body member consisting of an intermediate portion of the wire, and a two-ply cross-arm consisting of the end portions of the wire, the two limbs of the said body member being united at one end of said body member and unconnected with each other at the opposite end. 70

13. A wire fabric, including a plurality of links or units, each composed of a single piece of wire bent to form a two-ply body member, the two limbs of which are united at one end, said body member having a vertical loop at its other end, and said links being connected end-to-end to form longitudinal strands; and cross-connecting members flexibly connecting adjacent longitudinal strands, each of said cross-connecting members being formed with a terminal member transversely embracing the upper and under sides of the vertical loop of the link with which it is connected. 75

14. A wire fabric including a plurality of links or units, each composed of a single piece of wire bent to form a two-ply body member having its limbs joined at one end and having a loop at its opposite end, said links being connected end-to-end to form longitudinal strands and having adjacent longitudinal strands flexibly connected by cross-connecting members, each of which latter is formed with a terminal member embracing both sides of the loop of a link to which it is connected. 80

15. A wire link fabric including a plurality of links or units, each composed of a single piece of wire bent to form a body member, and a two-ply cross-arm, said cross arm consisting of the two end portions of the wire of the link extending laterally of the body member, and the two limbs of said cross-arm being spaced apart at their inner ends; said links being engaged with each other end-to-end to form longitudinal strands of the fabric and having the outer ends of their cross-arms engaged with the laterally adjacent links between the spaced limbs of the two-ply cross-arms of said laterally adjacent links. 105
